US0D1043253S

(12) **United States Design Patent** (10) **Patent No.:** **US D1,043,253 S**
(45) **Date of Patent:** **** Sep. 24, 2024**

(54) **BEVERAGE CONTAINER**

(71) Applicant: **MAGNOLIA INTELLECTUAL DESIGNS LLC**, Forney, TX (US)

(72) Inventor: **Mary Nicole Hamilton**, Heath, TX (US)

(73) Assignee: **MAGNOLIA INTELLECTUAL DESIGNS LLC**, Dallas, TX (US)

(**) Term: **15 Years**

(21) Appl. No.: **29/822,067**

(22) Filed: **Jan. 5, 2022**

(51) LOC (14) Cl. **07-01**

(52) U.S. Cl.

USPC **D7/536**; D7/510; D7/533

(57) **CLAIM**

The ornamental design for a beverage container, as shown and described.

DESCRIPTION

FIG. 1 is a front perspective view of my new design for a beverage container;

FIG. 2 is a rear elevational view thereof;

FIG. 3 is a front elevational view thereof;

FIG. 4 is a right side elevational view thereof, the left side elevational view being a mirror image;

FIG. 5 is a top plan view thereof; and,

FIG. 6 is a bottom plan view thereof.

The portions of the beverage container shown in broken lines form no part of the claimed design.

1 Claim, 5 Drawing Sheets
